Term of patent 14 years

(Cl. D24—1)

FIG. 1.

FIG. 2.

FIG. 3.

FIG. 5.

FIG. 4.

FIG. 1 is a perspective view of a dental instrument supporting and actuating unit, showing my new design;

FIG. 2 is a front elevation thereof;

FIG. 3 is a side elevation thereof looking toward the left side of FIG. 1;

FIG. 4 is a top plan view thereof; and

FIG. 5 is a side elevation thereof looking toward the right side of FIG. 1.

The dominant features of the design reside in the portions shown in full lines.

The rear of the unit, not shown, is substantially plain and unornamented.

I claim:

The ornamental design for a dental instrument supporting and actuating unit, as shown and described.
